ALTERNATING CURRENT CIRCUIT
BREAKERWerner Krämer, Berlin-Karishorst, Germany,
assignor to General Electric Company, a cor-
poration of New YorkApplication May 28, 1938, Serial No. 210,681
In Germany July 15, 1937

12 Claims. (Cl. 175—294)

My invention relates to alternating current circuit breakers, and more particularly to those of the synchronous type for effecting separation of the coacting breaker contacts only at or near a current zero.

Synchronous circuit breakers for interrupting alternating current power arcs have been proposed wherein the opening impulse initiates simultaneous movement of the engaged coacting contacts until a current zero is reached, whereupon an electro-magnetically controlled device arrests the movement of one of said contacts so that separation takes place at that time. This method of operation is highly desirable since it is recognized that the arc energy is greatly reduced and the arc-interrupting operation greatly facilitated when the extinguishing medium is applied coincident with contact separation at a current zero.

20 The devices heretofore proposed, however, have a number of inherent disadvantages such as, for example, excessive time lag due to too complicated control means or too great inertia. Also imperfect mechanical operation has been encountered 25 due to rebound when the retarding device engages the separating contact structure that is already moving at high speed.

The principal object of my invention is the provision of an improved synchronous circuit breaker of the aforesaid type that is effective 30 to apply within a very short and constant specific time after the opening impulse a positive retarding force to one of the contacts to cause high speed separation of the breaker contacts at or near a current zero.

My invention will be more fully set forth in the following description referring to the accompanying drawings, and the features of novelty which characterize my invention will be pointed out with 35 particularity in the claims annexed to and forming a part of this specification.

Referring to the drawings, Fig. 1 is a partly diagrammatic illustration of a synchronous electric circuit breaker embodying my invention 40 showing the contacts thereof in an intermediate position, and Fig. 2 is an enlarged detailed view partly in section showing a part of the retarding mechanism shown in Fig. 1.

The circuit breaker illustrated by way of example comprises a pair of relatively movable contacts 1 and 2, the socket contact 1 being designated as the fixed contact and the coacting rod contact 2 as the movable contact that is reciprocally operable along a rectilinear path with respect to the contact 1. For the purpose of sim-

plicity no special arc-extinguishing means is shown, it being understood that the present invention can be applied to various types of circuit breakers such as the well-known gas blast and oil blast types. The external circuit connections can be connected to the contact terminals as diagrammatically indicated at T.

The so-called fixed contact 1 is mounted for limited following movement with respect to the contact 2 by means of a compression spring 3 that is stressed in the closed circuit position. When the rod contact 2 is lowered to cause opening of the circuit the coacting fixed contact 1 remains in following engagement under the influence of the biasing spring 3 until the synchronous control embodying my invention arrests the movement of the contact 1 at or near a current zero.

The synchronous control means comprises essentially an electromagnet generally indicated at 4, having a coacting armature 5 that is connected to a detent 6. The detent is adapted to coact with a brake device 7 for controlling, in a manner presently described, the contact 1. In general, the arrangement is such that the detent 6, which is spring biased toward the brake device 7, is released so as immediately to stop the movement of contact 1 through the brake device when the magnet flux at the armature 5 indicates a current zero.

The coils 4' of the electromagnet are normally energized from a suitable synchronous control source, such as a current transformer 8 that is related to the circuit to be interrupted. The armature 5 coacts with the magnet pole pieces 5' that are spaced by a comparatively short air gap as illustrated so that the holding force acting on the armature when the magnetic circuit is closed is large, and the attracting force after initial movement of the armature from the pole pieces is comparatively small. The detent 6 is directly connected to the armature 5 through a connecting rod 9 and is biased by a spring 10 (Fig. 2) that is mounted within a fixed housing 11 in a direction opposing the holding force of the magnet and toward the brake device 7. The detent 6 is also guided for reciprocal rectilinear movement within a bushing 12 that is mounted in the frame of the magnet.

When an overload or short circuit occurs the movable contact 2 is moved downward towards the open circuit position at high speed by conventional operating means (not shown), the contact 1 during the initial opening movement tending to follow the rod contact under bias of spring 3. For the purpose of arresting the movement of

the contact 1 in the manner above described, the brake device 7 is connected through an endless belt or cable 13 to the contact 1 at 13' as illustrated. The belt is also adapted to carry the brake device 7 so that stopping of the brake device necessarily results in stopping of the contact 1. The belt 13 in the present instance is mounted on a fixed pulley 14 and a brake roller 15, an idler roller 16 being provided for adjustment of belt tension and for positioning the belt portions carrying the brake device and contact respectively.

Referring more particularly to Fig. 2, the brake device 7 comprises a longitudinal housing 17 that is connected at its opposite ends at 18 and 19 to the belt 13. The housing 17 is slotted at opposite sides thereof for permitting entries at one side of the detent 6 and at the opposite side for a fixed guide and positioning member 20. Mounted within the housing 17 is a stack of individual steel plates 21. As illustrated, the width of the plates is uniform and appreciably less than the corresponding dimension of the housing 17 so that the fixed member 20, which extends within a slotted wall of the housing, can realine the plates opposite thereto in abutting relation to the opposite wall. The plates 21, as previously indicated, are individually movable and are held in a given position simply by friction except when otherwise restrained. In the normal closed circuit position of the apparatus, a cam plate 22 secured to the housing 17 at the upper part thereof is opposite the detent 6 in abutting relation thereto so as to hold the detent and armature retracted against the bias of spring 10.

Accordingly, in response to the circuit opening impulse above referred to, the contact 1 starts to move downward with the rod contact 2 and the brake device 7 carried by the belt 13 simultaneously moves upward to a position such as shown in Fig. 1 wherein the cam plate 22 has cleared the detent 6. In this position the armature 5 is held only by the flux of the magnet 4. When, now, the current in the main line approaches or reaches the zero value, the detent 6 is released through the armature 5 so that the biasing spring 10 is immediately effective to project the detent 6 through the slotted wall of the housing 17 to displace certain of the plate members 21. As shown in Fig. 2, the detent in this position overlaps one of the undisturbed lower plates, thereby latching and blocking immediately further upward movement of the housing 17 and belt 13.

The movement of the contact 1 is therefore promptly arrested at a current zero by the detent 6 and by the brake roller 15 which can function in a manner similar to a band brake. Preferably, the speed of the contacts at the instant of contact separation is of the order of magnitude of 3 to 4 meters per second. The speed of the braking operation can be furthermore increased by designing the movable parts including the detent 6 of comparatively small hardened steel parts, so that the inertia is small, and also by relating the cam 22 and detent so that the stroke thereof is very short. Notwithstanding practically instantaneous stopping of the movable structure, the stresses on the braking device are not large by reason of the belt and brake roll arrangement.

The circuit-closing operation is effected by lifting the contact 2 in the usual manner so as to engage the contact 1 and force the same 75 against the bias of spring 3 to its upper initial

position. During this movement the belt 13 is moved a corresponding distance carrying downward with it the brake device 7, so that the fixed guide member 20, by reason of its rounded camming surface 20', progressively moves the steel plates 21 to their original aligned positions abutting the left wall of housing 17. At the end of the stroke the cam member 22 engages the coacting cam surface 6' of the detent 6 to force the same and the armature 5 to the reset position 10 shown in Fig. 1. Since the plate members 21 and the detent 6 are now reset, the apparatus is in readiness for another circuit-opening operation as above described.

For the purpose of mounting the magnet 4 so that the armature 5 is not loosened by vibration, the armature frame can be resiliently mounted at 23 to a fixed supporting plate 24. The detent spring 10 which is mounted within the housing 17 is, however, mounted in fixed relation to a support 25.

In order to overcome the initial inertia of the movable structure, a biasing spring 26 acting on the brake device 7 is provided for accelerating the circuit-opening movement of the mechanism. 25

The inertia of the movable structure including the detent 6 necessarily introduces a slight delay in arresting the contact structure 1 and, for this reason, it may be desirable to provide means for displacing the phase of the magnet current with respect to the main line current so that the armature 5 is actually released slightly before the current zero in the main circuit. This phase displacement provides sufficient time for the necessary mechanical operation of separating 35 the contacts 1 and 2 or even slightly before a current zero in the main circuit.

A current transformer such as shown is particularly adapted for this use since in any current transformer the primary ampere turns are equal to the secondary ampere turns plus the magnetizing ampere turns. Therefore, if the secondary circuit has a higher power factor than that of the magnetizing current, the secondary current will lead the primary current and the respective current zeros will be advanced accordingly in the secondary circuit. Since the magnetizing current is generally lagging to a considerable extent, and since the secondary circuit can readily be given a much higher power factor by inserting resistance, for example, the degree of lead of the secondary current can readily be adjusted as desired. 40

Another expedient is the use of an air gap in the current transformer core which increases the amount of the magnetizing current and, accordingly, tends to increase the lead in the secondary circuit. It may be noted that as the primary current is increased the magnetizing current is also increased so that the proportional amount of lagging current will be greater thereby increasing the lead of the secondary current. For example, a 45 degree lead in the secondary circuit can readily be secured under heavy current conditions when the interrupting duty is more 60 severe. This 45 degree lead allows 0.002 second for the latch to function in a 60 cycle system, or 0.005 second on a 25 cycle system. Accordingly, the time constant of the latch or detent can readily be compensated so that separation 70 of the contacts takes place as near the current zero in the main line as desired.

In case a series coil instead of a transformer as illustrated is used, the magnet poles can be encircled with so-called lag rings for delaying 75

in a well-known manner the release of the armature until after a current zero in the magnet coil. This of course would be in the opposite direction to the lead that is desired but if, for example, the magnet were lagged 80 degrees the following current zero would then be anticipated by $180^\circ - 80^\circ$ degrees or 100 degrees. This would provide 0.0045 second in a 60 cycle system which in the case of slightly sluggish operation of the 10 detent would insure separation of the contacts 1 and 2 substantially at or before the following current zero.

It should be understood that my invention is not limited to specific details of construction and 15 arrangement thereof herein illustrated, and that changes and modifications may occur to one skilled in the art without departing from the spirit of my invention.

What I claim as new and desire to secure by 20 Letters Patent of the United States is:

1. A synchronous electric circuit breaker comprising relatively movable contacts, said contacts arranged initially to move in following relation, means coacting with one of said contacts for arresting it to cause contact separation at a current zero including an electromagnetic device having means for restraining said one of said contacts with respect to continued following movement, and means relating said electromagnetic device 25 to the circuit controlled by said breaker for shifting the phase of the energizing current of said device with respect to the current in said circuit.

2. A synchronous electric circuit breaker comprising relatively movable contacts, said contacts arranged initially to move in following relation, means for arresting the movement of one of said contacts to cause contact separation at a current zero including an electromagnet having a restraining member coacting with said one of said contacts, and a current transformer related to the circuit controlled by said breaker for energizing said electromagnet to cause actuation of said restraining member, the secondary circuit of said current transformer having a higher 40 power factor than that of the magnetizing current whereby the phase of the magnet current is advanced with respect to the current in said circuit.

3. A synchronous electric circuit breaker comprising relatively movable contacts, means for controlling one of said contacts to cause contact separation at a current zero including an electromagnet having restraining means coacting with said one of said contacts, and means for energizing said electromagnet from the circuit controlled by said breaker, said means having such circuit characteristics that the phase of the magnet energizing current is advanced with respect to the current phase of said circuit for compensating the inertia of said restraining means.

4. A synchronous electric circuit breaker comprising relatively movable contacts, means coacting with one of said contacts to cause contact separation at a current zero including an electromagnet having a movable armature, a latching member connected to said armature, a spring for biasing said member in opposition to the magnet holding force at said armature in a direction to latch said one of said contacts, means controlled by the position of said contacts for holding said member retracted against the bias of said spring, said last-named means releasing said member after predetermined initial contact movement, and an energizing circuit for relating

said electromagnet to the circuit controlled by said breaker.

5. A synchronous electric circuit breaker comprising relatively movable contacts, means for maintaining said contacts in engagement for simultaneous movement thereof at the initiation of the contact opening operation, means for positively arresting the movement of one of said contacts to cause contact separation at a current zero comprising an electromagnet having a movable armature, a latching member connected to said armature, a spring for biasing said armature in opposition to the magnet holding force for moving said member to a latching position with respect to said one of said contacts, said spring being adapted to actuate said latching member after initiation of the contact-opening movement when the magnet energizing current drops to zero, and means relating said electromagnet to the circuit controlled by said breaker for energizing said magnet, said last-named means having a phase-shifting characteristic for relating the time constant of said spring biased member and the phase of the magnet-energizing current for causing application of said latching member at or near a current zero of said circuit.

6. A synchronous electric circuit breaker comprising relatively movable contacts, means coacting with one of said contacts to cause contact separation at a current zero including an electromagnet having a movable armature, a detent connected to said armature, a spring for biasing said detent in opposition to the magnet holding force at said armature in a direction to restrain said one of said contacts, means operable by said contacts for holding said detent retracted against the bias of said spring only in the closed circuit position of said contacts, and means relating said magnet to the circuit controlled by said breaker for energizing said magnet, said last-named means having a phase-shifting characteristic for relating the time constant of said spring biased detent and the phase of the magnet-energizing current for causing application of said detent after initiation of the contact opening operation at or near a current zero of said circuit.

7. A synchronous electric circuit breaker comprising relatively movable contacts, means for maintaining said contacts in engagement for simultaneous movement thereof at the initiation of the contact-opening operation, means for positively arresting the movement of one of said contacts to cause contact separation at a current zero comprising an electromagnet related to the circuit controlled by said breaker, a brake device including a flexible member operatively connected to and movable with said one of said contacts, and a latching member coacting with said brake device controlled by said electromagnet.

8. A synchronous electric circuit breaker comprising relatively movable contacts, means maintaining said contacts in engagement for simultaneous movement at the initiation of the contact-opening operation, means for positively arresting the movement of one of said contacts to cause contact separation at a current zero comprising an electromagnet related to the circuit controlled by said breaker, a latching device controlled by said electromagnet, means adapted to be latched by said device and a flexible member interconnecting said one of said contacts and said means.

9. A synchronous electric circuit breaker comprising relatively movable contacts, resilient means for biasing one of said contacts into fol-

lowing engagement with a coacting contact at the initiation of the contact-opening operation, means for positively arresting the movement of said resiliently biased contact to cause contact separation at a current zero comprising an endless belt connected to said resiliently biased contact, an electromagnet related to the circuit controlled by said breaker, a latching member controlled by said electromagnet, and means coacting with said latching member likewise carried by said belt arranged so that latching thereof arrests movement of said resiliently biased contacts.

10. A synchronous electric circuit breaker comprising relatively movable contacts, resilient means for biasing one of said contacts into following engagement with a coacting contact at the initiation of the contact-opening operation, means for positively arresting the movement of said resiliently biased contact to cause contact separation at a current zero comprising an electromagnet energized from the circuit controlled by said breaker having a movable armature, a latching member connected to said armature, a spring for biasing said armature in opposition to the magnet holding force for moving said latching member toward a latching position, a cam member movable in accordance with movement of said resiliently biased contact for holding said latching member in retracted position against the bias of said spring whereby said armature is in the closed magnetic circuit position, and means operatively connected to said resiliently biased contact adapted to be engaged by said latching member when said armature is released at a current zero following movement of said cam to an unobstructing position.

11. A synchronous electric circuit breaker comprising relatively movable contacts and means for restraining one of said contacts to cause con-

tact separation at a current zero including an electromagnet energized from the circuit controlled by said breaker having a movable armature, a latch connected to said armature, a spring for biasing said armature in opposition to the magnet holding force, a cam member movable in accordance with predetermined movement of said contacts for restraining said latch against the bias of said spring and for holding said armature closed, and means connected to and movable with said one of said contacts adapted to be engaged and restrained by said latch when said armature is released at a current zero following movement of said cam to an unobstructing position.

12. A synchronous electric circuit breaker comprising relatively movable contacts and means for restraining one of said contacts to cause contact separation at a current zero including an electromagnet energized from the circuit controlled by said breaker having a movable armature, a latch connected to said armature, a spring for biasing said armature in opposition to the magnet holding force, a cam member movable in accordance with predetermined movement of said contacts for restraining said latch against the bias of said spring and for holding said armature closed, and a latch receiving structure connected to and movable with said one of said contacts having a plurality of individually movable members adapted to be displaced by said latch when said armature is released at a current zero following movement of said cam to an unobstructing position, the undisplaced members blocking further movement of said structure, and means for restoring said members to reset position in accordance with the circuit-closing operation.

WERNER KRÄMER.
